UNITED STATES PATENT OFFICE

EDGAR BOURQUIN, OF FRAMINGHAM, MASSACHUSETTS, ASSIGNOR TO WARREN
TELECHRON COMPANY, A CORPORATION OF MAINE

DESIGN FOR A CYCLOMETER CLOCK CASE

Application filed February 9, 1933. Serial No. 47,159. Term of patent 14 years.

To all whom it may concern:

Be it known that I, EDGAR BOURQUIN, a citizen of the United States, residing at Framingham, county of Middlesex, State of Massachusetts, have invented a new, original, and ornamental Design for a Cyclometer Clock Case, of which the following is a specification, reference being had to the accompanying drawing, forming a part thereof.

The figure is a front perspective view of a cyclometer clock showing my new design.

I claim:

The ornamental design for a cyclometer clock case as shown.

In witness whereof, I have hereunto set my hand this third day of February, 1933.

EDGAR BOURQUIN.
